UNITED STATES PATENT OFFICE.

SAMUEL S. WALKER, OF WARREN, RHODE ISLAND.

SHUTTLE-CHECK FOR LOOMS.

SPECIFICATION forming part of Letters Patent No. 366,358, dated July 12, 1887.

Application filed February 23, 1887. Serial No. 228,485. (No model.)

To all whom it may concern:

Be it known that I, SAMUEL S. WALKER, of Warren, in the county of Bristol and State of Rhode Island, have invented certain new and useful Improvements in Shuttle-Checks for Looms; and I do hereby declare that the following is a full, clear, and exact description thereof, reference being had to the accompanying drawings, and to the letters of reference marked thereon, which form a part of this specification.

This invention relates to shuttle-checks for looms, and particularly to the springs which serve to press inward the binders in the sides of the shuttle-boxes into position to properly engage with and press upon the shuttle; and the object of the invention is to provide an improved construction which shall be more durable than those constructions heretofore in use. The invention will first be described in connection with the accompanying drawings, and then be defined in the claim at the end of the specification.

Figure 1 shows a part of a loom in vertical cross-section, taken through the line *x* *x* in Figs. 2 and 3, only those parts of the loom being shown that will assist in explaining the invention. Fig. 2 is a front elevation of a part of the loom-lathe. Fig. 3 shows a top view of the parts represented in Fig. 2.

The same letters are used to denote like parts, and where the parts are dotted in, the mark ' is added to the letter.

A represents a part of the end frame of a loom.

B is a portion of the lathe, which is constructed and operated in the usual way by means of the crank-shaft *v* through the connecting-bar *d*.

r is the "binder" in the side of the shuttle-box, and *o* is the finger that presses against the binder. This finger *o* is secured by means of a set-screw to the rod *a*, which is held free to turn in bearings attached to the side or bottom of the lathe. The binder-spring *c* is coiled around the rod *a* and has one end inserted in the collar *e*, secured to the rod *a* by means of a set-screw, *f*. The other end of the spring *c* is extended out back so as to reach the connecting-bar *d*, on the side of which a loop of leather, *s*, is attached by a screw,

through which loop the end of the spring *c* passes with a slight allowance for motion.

It will readily be seen that by pressing down on the long end of the spring *c* the torsion will turn the rod *a* by the collar *e*, in which the other end of the spring is held, and cause the finger *o* to press on the binder *r*, and that raising the same end of the spring will remove that pressure. This pressing down and raising of the spring is accomplished at the right time by connecting the long end to the bar *d*, as shown in Fig. 1. The motions will be such that as the lathe *B* moves back for the shed to be opened and the shuttle to be thrown the bar *d* will go over the upper part of its motion (see dotted lines *d'*) and the pressure of the spring *c* will be taken off the binder *r* and the shuttle left free to leave the box, and as the shuttle is being received at the other box the bar *d* will be on its downward motion and increasing the pressure of the spring *c* on the binder in that box, and the shuttle will be received with a gradual increasing pressure of the finger on the binder, that will stop it gradually and prevent any rebound.

The removal of the pressure from the shuttle in this manner is an important advantage, as any friction on the shuttle at that time exerts its retarding power on the long end of the lever or picker-stick, and this resistance is multiplied greatly on the running parts of the loom, increasing materially the power required to operate it, and also the wear.

In the usual way of applying the binder-spring the pressure on the binder is constant and the loom has to be run at a certain speed, so as to throw the shuttle with sufficient force to enter the box properly and not rebound, and if the speed of the loom slack up a little the shuttle will not be thrown with force sufficient to enter the box, and if the speed of the loom is increased beyond the limit the shuttle will be thrown with so much force as to cause it to rebound from the box. In the present arrangement the change in the speed of the loom that varies the force with which the shuttle is thrown also varies somewhat the action of the spring on the binder. This follows from the slight yielding of the parts that move the picker-stick and the springing of that stick under a suddenly-increased impulse, it result-

ing from this that the shuttle does not arrive at the binder quite so soon, relatively, as it would at the usual speed, while the finger *o*, under the influence of the spring moved by 5 the connecting-bar, having nothing to prevent it, is closed on the binder a little harder when the shuttle does enter, and by the increased friction prevents a rebound, so that the bad effects of a change in the speed of the loom are o avoided.

I am aware that a spring-arm has been attached to the rod that holds the binder-finger and moved by the contact therewith of a pin on the pitman or connecting-bar to the crank, 5 as shown in Patent No. 8,984, January 1, 1852, and in English Patent No. 2,032 of 1857, for a similar invention, the construction, however, having no coil or spiral spring, the spring in the arm itself being the only means for avoiding a positive pressure on the binder. With 20 this construction the spring effect was limited

by the shortness of the arm, while the greater length of material in my coiled spring, which is used as a torsion-spring, affords a greater amount of resiliency and opportunity for obtaining a nicely-graded effect with great durability, which is very important in view of the great number of vibrations performed. 25

Having thus described my improvements, what I claim as my invention, and desire to 30 secure by Letters Patent, is—

The lathe *B*, crank-shaft *v*, and connecting-bar *d*, in combination with the rod *a*, finger *o*, binder *r*, and spring *e*, the spring being coiled around the rod and having one end attached to the rod, and the other end extended out and connected to the bar *d*, substantially as and for the purpose set forth. 35

SAMUEL S. WALKER.
